UNITED STATES PATENT OFFICE.

PETER WILLIAM ROHDE, OF NEW YORK, N. Y., ASSIGNOR OF ONE-HALF TO
MEINERS & SCHUETTE, OF SAME PLACE.

WATCH-BALANCE.

SPECIFICATION forming part of Letters Patent No. 380,769, dated April 10, 1888.

Application filed November 16, 1887. Serial No. 255,297. (No model.)

To all whom it may concern:

Be it known that I, PETER WILLIAM ROHDE, of New York city, New York, have invented a new and Improved Balance-Staff for Watches, 5 of which the following is a specification.

This invention relates to a balance-staff for watches, so constructed that the balance-wheel is not rigidly connected thereto, as heretofore, but is connected thereto by means of a yielding coupling.

I have found that when a watch is dropped or is otherwise roughly handled its principal injury results from the fact that the violent motion of the balance-wheel has a tendency to 15 break the pivots of the balance-staff, inasmuch as the motion of the wheel is communicated through the staff directly to its pivots. By connecting the wheel to the staff by a yielding coupling the pivots of the staff will not be 20 affected by the motion of the wheel. As a result I have found that a watch can be dropped on a floor without injuring the staff and without stopping the watch.

The invention consists in the various features of improvement, more fully pointed out in the claims.

In the accompanying drawings, Figure 1 is a back view of a watch provided with my improvement. Fig. 2 is a back view, on an enlarged scale, of the balance-wheel. Fig. 3 is a section, on an enlarged scale, on line *x*-*x*, Fig. 2. Fig. 4 is a similar section showing the parts under the effects of a concussion. Fig. 5 is a detail central section of the sleeve 30 *k*. Fig. 6 is a similar section of a modification.

The letter *a* represents the balance-bridge of a watch, having a socket for receiving one of the pivots of the staff *b*, the other pivot of which is received by the foot-hole *c*, as usual. 40 The staff *b* is provided with the roller *d*, with ruby-pin *e*, which is engaged by the forked end of the anchor for reciprocating the balance-staff, also as customary.

f represents the balance-wheel, heretofore 45 rigidly secured to the balance-staff by its rigid diametrical arm *g*. I propose to enlarge the opening in the arm *g* that receives the balance-staff to such an extent that the balance-staff passes loosely through the said opening and 50 that the balance-wheel has a lateral play around

the staff. The motion of the balance staff is transmitted to the balance-wheel, not through the arm *g*, as heretofore, but by means of an additional radial arm, *h*. One end of this arm *h* is secured to the staff *b*, while its other end enters an aperture in the balance-wheel *f*. This aperture is of such an enlarged size that the end of arm *h* has free play therein, as indicated in Figs. 3 and 4.

j is the hair-spring of the watch.

In order to properly center the balance-staff *b*, I use a conical sleeve, *k*, Fig. 5, that surrounds the staff and projects with its contracted end into the opening of arm *g*. A fine spring, *m*, serves to hold the sleeve *k* up and 65 in contact with arm *g*.

To prevent any lateral motion of the balance-wheel *f*, when the watch is thrown down, from drawing the staff sidewise, I surround the balance-wheel by a flange, *n*, secured to the 70 back plate, *o*. The distance between the periphery of the balance-wheel and this flange should be less than the distance between the balance-staff and the edge of opening in arm *g*. Thus the balance-wheel will be checked by 75 the flange *n* in its lateral motion before it can tear the staff from its pivotal supports.

When the watch is in use, the motion of the anchor reciprocates the staff, and the latter (properly centered by sleeve *k*) reciprocates 80 the balance-wheel in the proper manner by arm *h*.

If the watch should fall, the arm *g* of balance-wheel will either by direct or rebound motion force the sleeve *k* downward against the action 85 of spring *m*. The motion of the balance-wheel will not disturb the staff, as neither the arm *h* nor the sleeve *k* transmits such motion to the staff. The downward motion of the sleeve *k* will open the central hole in arm *g* to a greater 90 or less extent to permit a lateral motion of the balance-wheel in addition to the upright motion. The lateral motion will, as already described, be checked by flange *n*, Fig. 4, before it affects the balance-staff, and thus the 95 staff will remain always in its normal central position without becoming strained. If the disturbing influences cease, the spring *m* forces the sleeve *k* back into its normal position.

In the modification illustrated in Fig. 6 the 100

balance-staff is surrounded by a cone, k' , rigidly fixed to the balance-staff. A yielding sleeve, k^2 , bears against the lower side of the arm g by spring m . In its normal position 5 the cone k' centers the balance-staff. Under disturbing influences the arm g of balance-wheel depresses sleeve k^2 , and as the arm descends the distance between the face of the cone k' and the central opening in arm g is increased. Thus lateral motion of the balance-wheel is permitted that will not affect the staff.

What I claim is—

1. The combination of a balance-staff with a balance-wheel, and with a yielding centering-sleeve loosely surrounding the staff, and with an arm connecting the staff with the wheel, substantially as specified. 15

2. The combination of balance-wheel having a perforated arm, with balance-staff passing loosely through said perforation, and with a yielding centering device, and with a radial arm connecting the balance-wheel with the balance-staff, substantially as specified. 20

3. The combination of balance-wheel having a perforated arm, with balance-staff passing 25

loosely through said arm, and with a yielding centering device, and with a radial arm connected at one end to the staff and entering with the other end an enlarged opening in the balance-wheel, substantially as specified. 30

4. The combination of balance-wheel having a perforated arm, with balance-staff passing loosely through said arm, and with a conical centering device, and with a radial arm connecting the balance-wheel with the staff, substantially as specified. 35

5. The combination of a balance-wheel with a balance-staff, and with a yielding centering device, and with a flange around the balance-wheel, substantially as specified. 40

6. The combination of balance-wheel having perforated arm, with balance staff passing loosely through said arm, and with a centering device, and with a connecting-arm, and with a flange around the balance-wheel, substantially as specified. 45

PETER WILLIAM ROHDE.
